UNITED STATES PATENT OFFICE.

ALTEN S. MILLER, OF BALTIMORE, MARYLAND.

TIME FUSE.

Application filed September 28, 1917, Serial No. 193,690. Renewed November 27, 1922.

To all whom it may concern:

Be it known that I, ALTEN S. MILLER, a citizen of the United States, residing at Baltimore, in the State of Maryland, have ⁵ invented certain new and useful Improvements in Time Fuses, of which the following is a specification.

This invention relates to improvements in time fuses for shells, projectiles, bombs, ¹⁰ grenades or the like, and has particular reference to a fuse that is designed to do the particular work for which it is intended at a predetermined time after being set in operation.

¹⁵ As heretofore constructed, fuses employing time powder trains vary in their time of burning according to the variations in pressure of the external atmosphere. For this reason variations in the time of burning occur if the fuses are employed in mountainous regions, or in high altitudes, as when used in anti-aircraft shells, and the operations desired are often delayed until comparatively long periods after the time the ²⁰ fuse has been set to operate, or to effect an explosion, with the result that they are ineffective of the desired result.

These inaccuracies in the time of burning are due to the fact that the higher the altitude in which the fuse is used the less will ³⁰ be the pressure under which the powder-train must burn, and the slower will the burning be. Consequently, if the time rings, in the case of a shell, are adjusted to effect an explosion at the termination of a given ³⁵ number of seconds, and the shell then fired into the air to a considerable altitude, the higher the shell is projected, the slower will the powder train burn, and the explosion, in ⁴⁰ the case of a shell, will not take place at the end of the predetermined number of seconds indicated by the time rings.

By means of my invention, I overcome ⁴⁵ these serious objections by providing a time fuse in which I maintain a substantially uniform internal pressure on the burning powder train irrespective of the external atmospheric pressures, with the result that the operation to be produced by the burning ⁵⁰ powder train, will take place at the time desired.

One object therefore of the present invention is to provide a fuse having a time-powder-train with means to cause said train

to burn at an approximately uniform rate of ⁵⁵ speed, irrespective of a wide range of variations in external atmospheric pressure.

Another object of the invention is to provide means whereby to maintain a practically uniform internal pressure on the time-powder-train regardless of a materially ⁶⁰ lesser external atmospheric pressure.

Another object is to construct a time fuse in an improved way to vent the gases and relieve the internal pressure caused by the ⁶⁵ burning powder-train, after those pressures have reached a predetermined point.

A still further object of the invention is to combine in a fuse employing a time-powder-train, a vent and an improved automatic ⁷⁰ pressure-equalizing means operating between the powder-train and vent, to permit the escape of the excess pressure in the form of gases generated by the burning powder and maintain a more nearly uniform pressure ⁷⁵ condition on the powder-train, whereby to cause the powder to burn at a substantially predetermined rate of speed.

With these, and other objects in view, a ⁸⁰ form of structure for carrying the inventive idea into practical effect is disclosed, it being understood however that the invention is not to be restricted to the form or structure shown.

In the drawing:

Fig. 1, shows the improved fuse located in a shell of shrapnel form,—the parts being illustrated in vertical longitudinal section, and

Fig. 2, illustrates a modified form of pressure controlling device,—also in vertical section.

The inventive idea of my time fuse may find expression in various forms, and the same may be embodied in various kinds of shells, projectiles, bombs, grenades or like devices, so that the present illustration showing the fuse in a shrapnel shell, is in no way to be construed as defining the structure or the scope or use of the invention.

Referring to the embodiment of the invention shown in Fig. 1, of the drawing, the numeral 5, designates a shell casing of the shrapnel type, provided at the forward end with a suitable plug 6, which latter is provided with a chamber 7, and which also has passages 8, leading therefrom, which passages communicate with the time-powder-train ¹⁰

grooves 9, and 10, in the time-rings 11 and 12, respectively.

A suitable plunger device 13, is located at the outer end of the plug 6, by means of which and upon the shock of firing, ignition of the powder-train in the groove 10, will take place to start the timing operation.

All of the above designated devices are old and well known, and their brief mention here is believed to be sufficient to aid in the disclosure of the present invention.

Beyond the plug 6, the shell has a metal cap 14, and channels 15, extending therethrough,—the inner ends of these channels 15 being in communication with the time-train grooves in the time-rings, whereby to vent the latter of gases generated by the burning powder-train while the shell is in flight. These vent channels have heretofore been 20 provided to vent the gases generated by the powder train in the shell, said gases passing through vent apertures 16, that have been provided in the nose 17, of said shell.

Various means may be employed in the 25 fuse to maintain a uniform internal pressure on the powder train, as will be seen from the present disclosures, but in the form of structure disclosed in Fig. 1, I interpose a valve device between the vent channels 15, and 30 the external vent apertures 16, which valve will remain seated until a predetermined pressure on the channel side is reached, whereupon it will unseat and allow gas to escape and so prevent an excess pressure in 35 the channels and on the time train.

In the form of structure disclosed in Fig. 1, which, as stated, is intended for illustrative purposes only and not in any way as defining the scope of the invention, I provide a cavity 18, in which the outer ends of the channels 15, terminate, and the outlet from said cavity is controlled by a valve 40 structure 19.

In the present instance the valve 19, has 45 the form of a puppet valve in that it has an annular flange 20, that seats around the cavity 18, and is guided in its movement toward or from the seat by means of guide pins 21, which prevent lateral displacement of the 50 valve during the shock of firing or while the projectile in which the fuse is located is in flight. The valve, in this instance, is of a conical form with its apex projecting toward the nose-end of the shell.

The nose-end of the shell is provided with 55 a conical casing 17, the interior base-end of which is rigidly attached to an internally-threaded bushing 22, that has threaded engagement with the body 14.

On the interior of the nose casing 17, I 60 provide a pressure receptacle 23, which, in this instance, has the form of a dome whereby to produce a chamber 24, for a purpose presently to be explained. This pressure 65 receptacle, in this instance, has an annular

flange 25, around the base of the dome, which flange is provided with a plurality of ports 26, and the extreme end portion 27, of the flange is formed into a ring-shape and has threaded engagement with the bushing 22, whereby to secure the same in an encircling position with respect to the valve 19.

The purpose of the pressure receptacle is to provide means that is not affected by external atmospheric pressures, for exerting a predetermined pressure on the upper side of the valve 19, whereby to keep the valve 75 yieldingly pressed to its seat, but which will permit the valve to unseat when the pressure on the lower side exceeds that on the upper side, and in this way will maintain a substantial equalization of pressures on the opposite sides of the valve.

In the present instance, the means employed in the pressure receptacle to transmit the desired pressure, is a diaphragm 28, which extends across the base of the dome and closes the bottom of the dome-chamber 24, and on the upper side of this diaphragm 90 and confined in the chamber is a fluid, such as air or gas. This fluid-pressure in the dome-chamber exerts a constant predetermined pressure on the upper side of the diaphragm and keeps the latter pressed down 95 on top of the valve 19, whereby to normally keep the latter seated over the chamber 18, and the outer ends of the vent-channels 15. Of course, in practice the relative areas of the valve and diaphragm are such that no matter what the atmospheric pressure on the exterior of the shell or on the interior of the nose casing 17, and fuse may be, the valve 19, will be kept seated by the pressure exerted by the pressure-means in the chamber 100 24, until the pressure in chamber 18, and passages 15, overcomes that in chamber 24, at which moment valve 19, will unseat and allow the excess pressure from the channels and on the time powder train to vent.

In the device illustrated in Fig. 2, of the drawing, the fuse structure is substantially the same as that disclosed in Fig. 1, in that it employs the channels 15, plunger 13, and valve 19, but the pressure means employed for keeping the valve seated at a predetermined pressure is slightly modified.

In this modified form, the pressure receptacle has a cylinder 29, with a piston head 30, snugly fitting and closing the lower end thereof, and a spring 31, is located in the cylinder and exerts the desired pressure on the upper side of the piston-head. The lower side of the piston-head seats on the upper end of the valve 19, and holds the latter down on its seat whereby to confine the gases in the passages 15, until the predetermined pressure is reached, whereupon the valve lifts to vent the excess gases.

In this instance a vacuum should be 130

formed in the cylinder 29, and on top of the piston,—provision being made at 32, in the top of the cylinder for the exhaust of the air.

5 In this modified form the pressure receptacle may have the same arrangement of flanges 25, and 27, and vent ports 26, as are shown in the device of Fig. 1.

In both forms of devices shown, I provide 10 a locking pin 33, which extends through the wall of the nose-casing 17; the bushing 22, and the flange portion 27, of the dome which effectively locks said parts together.

Having described my invention what I 15 claim is,—

1. In a time fuse, the combination with an exterior case, of a time powder-train on the interior of the case; valve means in the case on the escape side of the powder-train; 20 valve-seating means one side of which is operatively connected to the valve to seat the latter and a housing having a sealed chamber to the interior of which the opposite side of the valve-seating means is exposed.

25 2. The combination with a case, of a time powder-train in the case; valve-means also in the case on the escape side of the powder train; a housing in the case and having a chamber therein and a valve-closing device 30 sealing said chamber and said closing device exerting a seating pressure on the valve.

3. In a time fuse the combination with an exterior case, of a time powder-train on the interior of the case, valve means in the case 35 and movable in one direction to permit the gases generated by the burning powder train to escape from the case said valve means being held to its seat by a movable device one side of which movable device is exposed to 40 a chamber that is sealed against atmospheric pressure.

4. In a time fuse the combination with an exterior case, of a time powder-train on the interior of the case, valve means in the case 45 and movable in one direction to permit the gases generated by the burning powder train to escape from the case, a yielding device normally pressing the valve in a direction to close the same said yielding device having 50 one side exposed to a sealed chamber to-

ward which the valve moves to effect a venting of the generated gases.

5. In a time fuse the combination with an exterior case, of a time powder-train on the interior of the case, valve means in the case 55 and movable in one direction to permit the gases generated by the burning powder train to escape from the case, a receptacle in the same case with a movable device therein to close the same said movable receptacle- closing device engaging the valve means to 60 press the same toward its seat and said receptacle being sealed against atmospheric pressure.

6. A time fuse having a vent from the interior to the exterior, in combination with a time powder train, and means between said vent and the time powder train for maintaining a uniform interior pressure on the powder train irrespective of the exterior 70 pressure about the fuse.

7. A time fuse having a vent from the interior to the exterior, in combination with a time powder-train, valve means in the fuse between the vent and the powder-train and means for maintaining a closing pressure on the valve means independent of the atmospheric pressure.

8. In a time fuse the combination with a time powder train, of means for adjusting 80 the time train and means in the fuse for maintaining a predetermined pressure on the powder train irrespective of the pressures external to the fuse.

9. A time fuse having a vent from the interior to the exterior in combination with a time powder train, a valve and valve-closing means to control the escape of gases from the fuse said valve and valve-closing means having balanced surfaces that are subject to 90 atmospheric pressure and said valve-closing means maintaining a uniform closing pressure on the valve irrespective of variations of atmospheric pressure.

In testimony whereof I affix my signature 95 in the presence of two witnesses.
